UNITED STATES PATENT OFFICE

ETTORE BELLINI, OF PARIS, FRANCE

MULTIPLE-AMPLIFIER ARRANGEMENT

Application filed January 12, 1927, Serial No. 160,555, and in France February 2, 1926.

The present invention relates to multi-group amplifier tubes adapted to be substituted or interchanged one for another.

To make amplifiers capable of working at high efficiency over a very wide range of wave-lengths, it has been suggested to arrange between the input and the output terminals of the apparatus, several amplifiers comprising independent tubes, and each intended to insure operation of the apparatus inside a range or scale forming part of the field of application of the apparatus.

The substitution of one amplifier group for another according to the reception dealt with is insured by means of change-over switches. A switch disposed between the input terminals of the apparatus and the input terminals of each of the groups allows of uniting the group that has been chosen with the input terminals of the apparatus. Another switch arranged in a similar way so as to connect the output terminals of the apparatus with the output terminals of the particular group that is operative.

Now, these switches constitute an element of complication in circuit arrangements, making for higher cost of manufacture, but the most serious drawback is that these switches, especially the one at the input end, tend to introduce stray capacitance that is harmful so far as the operation of the apparatus at very high frequencies is concerned.

Now, the present invention obviates the said accessory parts and allows of a simplification of the connections. The features of the invention together with the objects and advantages thereof will best be understood by reference to the following description taken in connection with the accompanying drawing in which the single figure shows a circuit arrangement whereby either of two amplifier groups may be employed.

The desired result may be realized in the following manner: To one and the same input terminal *a* of the apparatus there is connected the grid of the first tube of each of the groups or banks of selective or replaceable amplifiers, 1 and 2. The tuned input circuit *b* has its inductance coil grounded substan-

tially at its mid-point, the joint heating-current source *A* also being grounded. Furthermore, to one and the same output terminal *c* of the apparatus there is connected the plate of the last tube of each of the said groups, the other terminal *d* being united with the common plate-current source *B*.

The change-over from one group or bank to another is then obtained and effected automatically by the starting of the filaments of the group to be put in service.

Having thus described my invention, I claim:

1. A radio receiving arrangement for use over a comparatively wide range of wave-lengths, comprising a common radio frequency input circuit capable of being tuned over the entire wave-length range, a common audio frequency output circuit, a plurality of independent groups of cascade-connected tube amplifiers arranged to operate within different bands of said range and connected between said common input and output circuits, and means for selectively rendering operative one of said amplifier groups by closing the filament heating-circuit of that group.

2. A radio receiving arrangement for use over a comparatively wide range of wave-lengths, comprising a common radio frequency input circuit having its inductance grounded at its mid-point and capable of being tuned over the entire wave-length range, a common audio frequency output circuit, a plurality of independent groups of cascade-connected tube amplifiers arranged to operate within different bands of said range and connected between said common input and output circuits, a grounded filament heating-circuit for said amplifier groups, and means for selectively rendering operative one of said amplifier groups by closing the filament heating-circuit for that group.

3. A radio receiving arrangement for use over a comparatively wide range of wave-lengths, comprising several independent groups of cascade-connected tube amplifiers, each group arranged to operate within a different band of the entire wave-length range, the grid of the first tube in each group being

connected to a common radio frequency input terminal, and the plate of each tube being connected to a common plate-current supply, except the last tube in each group which are connected together to one terminal of the audio frequency output, and means for selectively operating any one of said amplifier groups.

4. A radio receiving arrangement for use over a comparatively wide range of wave-lengths, comprising a common radio frequency input circuit capable of being tuned to wave-lengths within said range, a plurality of independent groups of cascade-connected tube amplifiers, each group arranged to operate within a different band of the entire wave-length range, the grid of the first tube in each group being connected to a common terminal of said input circuit, and the plate of each tube, except the last tube in each group, being connected to a common plate-current supply, and means for selectively operating any one of said amplifier groups.

5. A radio receiving arrangement for use over a comparatively wide range of wave-lengths, comprising a common radio frequency input circuit capable of being tuned to wave-lengths within said range, a plurality of independent groups of cascade-connected high-frequency, detector and low-frequency amplifier tubes, the grid of the first high-frequency amplifier tube in each group being connected to a common terminal of said input circuit, and the plates of the amplifier tubes, except the last tube in each group, being connected to a common plate current supply, and means for selectively rendering operative the desired amplifier group.

6. A receiving circuit for use over a comparatively wide range of wave lengths, comprising a common input circuit capable of being tuned over the entire wave length range, said input circuit being grounded, a common output circuit, a plurality of independent groups of cascade-connected tube amplifiers arranged to operate with different bands of said wave length range and connected between said common input and output circuits, a grounded filament heating-circuit for said amplifier groups, and means associated with said heating-circuit for selectively rendering operative only one of said amplifier groups.
